UNITED STATES PATENT OFFICE.

MATTHEW C. VAN ALSTYNE AND CHARLES H. VAN ALSTYNE, OF SOUTH HAVEN,
MICHIGAN.

OILER.

1,323,128.

Specification of Letters Patent. Patented Nov. 25, 1919.

Application filed March 10, 1919. Serial No. 281,853.

To all whom it may concern:

Be it known that we, MATTHEW C. VAN ALSTYNE and CHARLES H. VAN ALSTYNE, citizens of the United States, residing at 5 South Haven, in the county of Van Buren and State of Michigan, have invented certain new and useful Improvements in Oilers, of which the following is a specification.

Our invention relates to improvements in 10 oilers for use upon vehicle springs, and its objects are: first, to provide an oiler that may be readily removed and replaced; second, to provide a means whereby the vertical sides of the oiler may be readily removed and replaced.

We attain these objects by the mechanism and construction of parts shown in the accompanying drawing, in which Figure 1 is a plan of the oiler complete. Fig. 2 is a longitudinal section of the same practically on the line 3—3 of Fig. 3. Fig. 3 is an end elevation of the same showing the manner of interlocking the ends with the top, or oil containing part of the oiler.

Similar numerals indicate similar parts throughout the several views.

In the construction of this oiler we make use of a hollow top, or oil receptacle 1, the ends, 2, of which are turned downwardly 30 at right angles with the upper surface and are provided with a slot, 3, through each, for the passage of the lips 4 at the upper ends of the end pieces 6. We prefer that the upper ends of these pieces be offset, as at 35 5, for the formation of the lips 4, so said lips may be readily passed into and through, and taken out of the slots 3 by carrying the lower ends into practically the position indicated by the dotted lines.

The end pieces 6 must be made with the 40 edges formed at right angles with the bodies, as indicated at 7, so as to cover the edges of

the felt 9 and avert the danger of dust, &c., coming into contact with, and being absorbed by the wicking and vitiating the oil. 45

This construction is designed as an improvement upon our Patent Number 1,244,923, issued October 30, 1917, and renders the application of said oiler much more simple of attachment and removal. The 50 loops 10 are designed to receive and retain the springs 11, for securing the oiler in place, and pressing the wicking securely against the edges of the springs, when in use.

The oil container 1 of this oiler is made 55 hollow and has a wick, or felt packing in each end, so arranged that there will be a considerable open space between the upper ends of the wicks, and the sides of the wicks will extend downwardly, as at 9, far enough 60 to insure the oil with which it is saturated, to act upon the edges of each and all of the layers of the springs. The opening 8 is for the entrance of oil into the oil container.

What we claim as new in the art, is: 65

1. In an oiler for vehicle springs, a hollow oil container, the ends of the top of said container bent downwardly and provided with slots, end plates channeled and having a lip 4 formed thereon in position to be 70 made to pass through the slots in the tops of the oil container.

2. In an oiler for vehicle springs, a hollow oil container, the ends of the top of the container bent downwardly at right angles and 75 having a slot through each end, channel shaped ends having offsets forming lips arranged to be passed through the slots, and loops formed upon the lower ends of the end pieces. 80

Signed at South Haven Michigan, February 26th 1919.

MATTHEW C. VAN ALSTYNE.
CHARLES H. VAN ALSTYNE.
